UNITED STATES PATENT OFFICE.

CHARLES W. BECK, OF CHICAGO, ILLINOIS, ASSIGNOR, BY MESNE ASSIGNMENTS, TO ELECTROLITE GAS LAMP COMPANY, OF NEW YORK, N. Y.

ACETYLENE-GAS GENERATOR.

SPECIFICATION forming part of Letters Patent No. 790,867, dated May 23, 1905.

Original application filed August 29, 1896, Serial No. 604,255. Divided and this application filed November 20, 1896. Serial No. 612,810.

To all whom it may concern:

Be it known that I, CHARLES W. BECK, a citizen of the United States, residing at Chicago, in the county of Cook and State of Illinois, have invented certain new and useful Improvements in Lamps for Burning Acetylene Gas, of which the following is a specification.

This invention relates to improvements in lamps for generating and burning acetylene gas produced by the combination of calcic carbide with a suitable liquid slaking agent; and it is the particular object of the present invention to provide a construction in portable lamps (a bicycle-lamp in the embodiment illustrated) in which the transfer of the liquid slaking agent to the carbide is effected through the medium of a capillary siphon, thereby insuring a substantially uniform flow of liquid and a consequent uniform generation of gas and at the same time producing a lamp in which the flow of liquid is practically unaffected by jars and jolts transmitted to the lamp from the frame of the vehicle.

Further objects of the invention are to provide a construction in which the gas generated is passed through condensing and filtering devices on its way to the burner-jet and in which the supply of liquid is positively shut off at the same time that the burner is closed, thereby interrupting the generation of gas and consequent waste after the lamp is extinguished.

The invention consists in the matters hereinafter described, and more particularly pointed out in the appended claims, and the same will be readily understood by reference to the accompanying drawings, in which—

Figure 1 is an axial sectional view of a bicycle-lamp embodying my invention, the headlight portion thereof being of conventional form. Fig. 2 is a fragmentary detail showing the inner truncated end of the valve-plug and the valve-actuating rod connected therewith. Fig. 3 is an axial sectional view of the burner or jet nozzle and the upper end of the connected valve-sleeve.

Referring to the drawings, A designates as

a whole a headlight which may be of any desired and suitable form, and B the font or gas-generating device, suitably connected with the lower part of the headlight and provided at its top with a jet-nozzle C, arranged to project upwardly within the reflector A' of the headlight.

The font B consists generally of the bowl-shaped outer shell b, the upper portion of which is cylindric and closed at its upper end by means of a screw-cap B', arranged to close the said shell b hermetically except for the jet-nozzle or burner C, hereinbefore referred to. As a convenient construction for securing a gas-tight fit at the junction of the screw-cap with the shell, the former is shown as provided with a cylindric depending flange b', exteriorly screw-threaded to fit within the upper end of the shell b, and with a radially-outturned marginal flange b², which overlies a similar outturned flange b³, formed at the upper margin of the shell b. Between said flanges b² b³ is arranged a packing ring or washer b⁴. The cap B' is provided centrally with an upwardly-projecting extension B², of reduced diameter and of general cylindric form, adapted to fit within the depending spring petticoat-flange a of the headlight and provided at its upper end with a circumferential bead b⁵, over which the said spring-flange clasps.

D designates a liquid-receptacle suitably conformed to fit snugly but easily within the upper cylindric part of the shell b and of such depth as to extend downwardly within said shell approximately one-half of the depth of the latter. In order to support said liquid-receptacle in this position within the upper part of the shell, the latter is conveniently provided with an internal ledge or bead b⁶, herein shown as made by forming an external circumferential crease b⁷ in the body of the shell, upon which ledge the lower end of the liquid-receptacle rests. The liquid-receptacle D is of annular form—that is to say, it is provided with a relatively large open-ended tubular central passage B', extending entirely through the said recepta-

cle from top to bottom thereof—its lower end opening into the generating-chamber, so that the liquid-chamber is out of the vertical plane of the end of the passage which is in communication with generating-chamber. The top of the liquid-receptacle is closed by means of a cap or cover D^2 , provided with a central elevated portion D^3 , which extends upwardly within the similarly-shaped extension B^2 and is suitably apertured at its center to fit exteriorly upon the upper end of the tubular partition-wall d . Said cover D^2 is provided with depending flanges $d' d''$, which serve to retain the cover in position and insure close joints at the outer and inner margins, respectively, of said cover.

In use the calcium carbid X is placed within the lower part of the shell b , and it will be obvious that in such a construction wherein the carbid occupies the lower part of the font and the liquid the upper part thereof the automatic flow of liquid from the receptacle to the carbide may be effected by siphonage. To this end the tubular inner wall d of the liquid-receptacle is provided at its upper end above the liquid-level with a plurality of wick apertures or inlets d^6 , through which are inserted wicks K . The wicks K are each of such length as to extend at their inner ends within the liquid-receptacle to the bottom thereof and to depend at their other ends downwardly within the tubular passage to a point below the level of the bottom of the liquid-receptacle, said wicks extending laterally or horizontally from the liquid-chamber into the passage which connects the two chambers and serves to convey the liquid laterally from the liquid-chamber to the passage leading to generating-chamber. Obviously when thus arranged the wicks will absorb the liquid and act as capillary siphons to effectuate a practically uniform flow of liquid from one receptacle to the other. Preferably and as herein shown the depending ends of the wicks are arranged to extend through a mass of absorbent material H packed within said tubular chamber throughout a portion of its length, as indicated clearly in said Fig. 1, the object of this construction being both to retard the flow of liquid and to render the flow less susceptible to the effect of jolts and jars.

The object of locating the liquid-chamber out of the vertical plane of the liquid-inlet to the generating-chamber and causing the liquid in passing from the said fluid-chamber to flow laterally or horizontally through a body of pervious absorbent material for a portion of its movement to the generating-chamber is to secure a steady and uniform movement of the liquid and to permit of the use of an extended body of pervious material. It will be readily understood that the greater the length of pervious material through which the liquid passes the less effect will jars and

jolts of the liquid-chamber have on the uniformity of the feed, and by disposing this pervious material horizontally and causing all the liquid to pass laterally through this horizontal portion from the liquid-chamber to the generating-chamber the feed is still further protected from variations which would otherwise be caused by jarring the liquid chamber or receptacle. The liquid passes through the pervious material in a finely-divided condition and while in this condition is subjected to the pressure of the gas in the generating-chamber, the flow of liquid being therefore somewhat proportional to the gas-pressure.

I have ascertained by experiments that the gas becomes supercharged with aqueous vapor in the course of its generation in a lamp of the character described, so that water in the form of minute drops is liable to be carried up and form in the jet-nozzle and be forced therefrom, so as to interfere more or less with the proper burning of the gas, unless some means be provided for precipitating and collecting the superfluous moisture before the gas issues from the nozzle. I have therefore in the present instance provided condensing and filtering devices as follows: I designate a stand-pipe arranged concentrically within the tubular passage and in this instance supported at its lower end by means of a diaphragm d^7 , which extends across the lower end of the tubular passage, said diaphragm being suitably apertured for the passage of the ends of the wicks. The lower end of the stand-pipe is open, while at its upper end it is provided with a closure i , suitably perforated for the exit of gas. Preferably the upper part of the stand-pipe will be filled with a porous packing of filtering material i' .

In order to afford means for adjusting or regulating the flowing capacity of the wicks, I have herein shown a sleeve-section L threaded upon the outside of the tubular wall within the liquid-receptacle at a point immediately above the wick-apertures d^6 , which sleeve-section is provided at its lower end with a flaring or bell-shaped flange l , adapted as the sleeve is screwed downwardly to impinge upon the several wicks and by compressing them against the lower sides of the wick-apertures reduce their porosity and thus retard the flow of liquid therethrough to any desired degree. I have also provided means whereby the flow of liquid will be arrested when the gas-cock is turned so as to shut off or close the burner. This is accomplished by means of an inner sleeve M , which is fitted to slide within the upper part of the tubular passage immediately above the wick-apertures therein and is provided at its lower end with a flange m , substantially like that of the sleeve L . The upper end of said sleeve M is contracted and

is connected with the valve-plug G by means of an actuating-rod arranged as follows: At that part of said nozzle through which the valve-plug is inserted the body thereof is enlarged spherically, as indicated most clearly in Fig. 3, and the gas-passage therein is deflected from an axial line toward the base or larger end of the valve-plug, the gas-passage E through the latter being correspondingly located to register therewith. The smaller truncated end g' of the valve-plug terminates at a point within the body of the spherical enlargement, the latter being chambered or provided with a recess c , within which the said end of the valve-plug projects freely. A stud or wrist-pin g^2 is provided upon the face end of the valve-plug, located eccentrically to the axis of the latter, with which recess the upper end of the pitman or actuating-rod f is pivotally connected. The wrist-pin g^2 is located in such angular relation to the gas-passage g through the valve-plug that when the latter is oscillated to open and close the jet-nozzle the sleeve L will be correspondingly elevated or depressed to relieve or compress the several wicks K at the points where the latter merge from the liquid-receptacle. In order that the valve-plug G may be held within its seat, a screw G' is arranged to extend through the side wall of the jet-nozzle in axial alignment with the valve-plug and is engaged at its inner end with the end of the latter. In order to avoid interference with this retaining-screw, the actuating-rod F is curved, as indicated at f .

Inasmuch as the screw-cap B' of the font must be removed each time the lamp needs to be replenished it is necessary that the actuating-rod be also disconnected when the cap is removed and reconnected when the cap is returned to place, and this is conveniently accomplished by making the pitch of the screw-threaded connection between the end of the actuating-rod and the upper end of the sleeve L and the pitch of the screw-threads upon the margins of the screw-cap equal, so that in turning the screw-cap said parts will be simultaneously connected or disconnected, as the case may be. In order to hold the sleeve M from rotation when the screw-cap is being turned, I provide a guide-stud d^4 upon the inner tubular wall of the liquid-chamber, which stud is arranged to extend within a vertical slot e , formed in the sleeve L. Inasmuch as the upper end of the stand-pipe terminates within the valve-sleeve the latter is provided with apertures l' for the escape of the gas to the base of the burner-nozzle.

In order to hold the liquid-receptacle in form bearing upon the ledge b^6 and at the same time to insure that any gas which may pass upwardly between the outer walls of the liquid-receptacle and the shell b shall be filtered, I provide a felt or analogous washer or

packing J, which overlies the cover of the liquid-receptacle and is clamped at its margins, as at j , between said cover and the screw-cap of the font.

The operation of the lamp thus described is as follows: The screw-cap having been removed and the liquid-receptacle lifted out, the carbide is poured in, the liquid-receptacle filled and replaced in position. Upon turning the cock so as to open the nozzle C the valve-sleeve will be raised and the liquid permitted to pass downward through the wicks into contact with the carbide and will rapidly generate gas. The gas generated in the body of the carbide, having no other means of ready escape, is forced into the stand-pipe and thence up to the jet-nozzle, issuing from the latter with considerable force and burning when ignited in a bright strong jet.

While I have herein shown what I deem a preferred embodiment of my invention, yet it will be obvious that the details thereof may be modified to some extent without departure from the invention, and I do not, therefore, wish to be limited to the precise details shown, except as made the subject of specific claims.

I claim—

1. In a lamp for generating and burning acetylene gas, the combination of a chamber for the carbide, a superposed chamber for the fluid, a tube extending upwardly from the bottom of said chamber, and a capillary siphon or siphons extending from the charge of fluid through openings in the walls of the tube and thence downward through said tube into the chamber for the carbide.

2. In a lamp for generating and burning acetylene gas, the combination of a chamber for the carbide, a superposed chamber for the fluids, a tube extending upwardly from the bottom of said latter chamber, a capillary siphon or siphons extending from the fluid-chamber through openings in the walls of the tube and thence downward through said tube into the chamber for the carbide and a porous packing filling said tube around the reach of siphon therein and serving therewith to regulate the feed and as a filter for the ascending gas.

3. In a lamp generating and burning acetylene gas, the combination of a chamber for the carbide, a superposed chamber for the fluids, a perforated tube extending upwardly from the bottom of said latter chamber, a sleeve inclosed within said tube and opening above to a gas-duct, a stop-cock in said duct, a connection between said sleeve and the cock whereby it is reciprocated by the turning of the latter, and a capillary siphon or siphons leading from the fluid-chamber through the perforated tube to the carbide-chamber, against which siphon the sleeve is jammed to cut off the flow of fluid when the stop-cock is turned to close the duct.

4. In a lamp for generating and burning

acetylene gas, the combination with a compartment for the reception of carbid and generation of gas, and a superposed compartment for a charge of slaking fluid, of a perforated 5 tube rising through the fluid-compartment, siphon-wicks extending from the fluid-compartment through the tube into the carbid-compartment, a stand-pipe leading from the generating-compartment up through said 10 tube and having an inlet passage or passages at its lower end, and a packing between the stand-pipe and the tube, embracing the wicks.

5. The combination with the fluid-receptacle and the tubular passage-way there-through, and with the siphon wick or wicks and the apertures through which they enter 15 said passage-way, of the regulating-sleeve exterior to and adjustable upon the wall of said passage-way and flanged at its end to 20 press upon the wicks.

6. The combination with the fluid-receptacle and the tubular passage-way there-through, and with the siphon wick or wicks and the apertures through which they enter 25 said passage-way, of the cut-off sleeve movable within the tubular passage-way, and flanged at its lower end to jam against the wicks, and means whereby said sleeve may be adjusted up and down to release the wicks 30 or bear against them.

7. The combination with the fluid-receptacle and the tubular passage-way there-through, and with the siphon wick or wicks and the apertures through which they enter 35 said passage-way, of the cut-off sleeve sliding within the passage-way and flanged at its lower end to jam against the wicks, the stop-cock or plug-valve, and a connection between said valve and the sleeve, whereby the sleeve 40 is lifted away from the wicks when the valve is opened, and jammed against them when the valve is closed.

8. The combination with the fluid-receptacle and the tubular passage-way there-through, and with the siphon-wicks and the 45 apertures through which they enter said passage-way, of the regulating-sleeve exterior to and adjustable upon the wall of said passage-way, the cut-off sleeve movable within said 50 wall, and means for shifting the position of said latter sleeve, to cause it to jam against the wicks or release it therefrom.

9. The combination with the fluid-receptacle and the tubular passage-way there-through, and with the siphon-wicks and the 55 apertures through which they enter said passage-way, of the regulating-sleeve exterior to and threaded upon the wall of the passage-way above said apertures, and the cut-off 60 sleeve sliding within said way and also above the apertures, and means connected with the burner-valve for reciprocating said sleeve to jam it against the wicks or release it therefrom in turning the gas off and on.

65 10. In a gas-generator the combination

with a water-reservoir and with a generating-chamber below the reservoir, of a siphon-tube leading from the reservoir to the chamber, the reservoir and chamber being otherwise disconnected whereby the gas-pressure 70 developed within the chamber regulates the flow of the water by direct action upon the siphon.

11. In a gas-generator, the combination with a water-reservoir and with a generating-chamber below the reservoir, of a capillary 75 siphon leading from the reservoir to the chamber and means for applying pressure to compress the siphon whereby the flow of liquid therethrough is restricted.

12. In an apparatus for generating gas by the reaction of a liquid acting upon a solid, a closed generating-chamber for the solid, provided with a controllable gas-outlet, a liquid-chamber, an open-ended extended passage 85 connecting said chambers, the walls of said passage being imperforate and a body of pervious material obstructing said passage and serving to impede and regulate the flow of liquid to the generating-chamber, said generating-chamber being hermetically sealed, except for its gas-outlet, against access of outer air whereby the gas may be generated under pressure by controlling the said gas-outlet.

13. In an apparatus for generating gas by the reaction of a liquid acting upon a solid, a closed generating-chamber for the solid, provided with a restricted gas-outlet, a liquid-chamber, an open-ended extended passage 95 connecting said chambers, the walls of said passage being imperforate, and a body of pervious material obstructing said passage and serving to impede and regulate the flow of liquid to the generating-chamber, said generating-chamber being hermetically sealed, except for its gas-outlet, against access of outer air, whereby the gas may be generated under pressure.

14. In an apparatus for generating gas by the reaction of a liquid upon a solid, a closed generating-chamber for the solid provided with a restricted gas-outlet, a liquid-chamber, an extended passage connecting said chambers, said passage being formed throughout its length by imperforate immovable walls, and a stationary body of pervious material confined between said immovable walls said body of pervious material serving to impede and regulate the flow of liquid to the generating-chamber, said generating-chamber being hermetically sealed except for its gas-outlet, against access of outer air, whereby the gas may be generated under pressure.

15. In an apparatus for generating gas by the reaction of a liquid upon a solid, a closed generating-chamber for the solid provided with a restricted gas-outlet, a liquid-chamber, an extended passage connecting the two chambers, and a body of pervious material 13

obstructing said passage and serving to impede and regulate the flow of the liquid to the generating-chamber, said body of pervious material extending laterally between the two chambers so that the flow of liquid between the chambers will be lateral for a portion of its movement, and the liquid will be caused to flow through an extended body of pervious material before reaching the generating-chamber.

16. In an apparatus for generating gas by the reaction of a liquid upon a solid, a closed generating-chamber for the solid, a liquid-chamber, an extended passage connecting said chamber said passage being formed throughout its length by immovable walls, and a body of pervious material confined between said immovable walls, a part of said body of pervious material extending laterally between the two chambers so the flow of liquid between the two chambers will be lateral for a portion of its movement, and the liquid will be caused to flow through an extended body of pervious material before reaching the generating-chamber.

17. In an apparatus for generating acetylene gas, a closed generating-chamber for the carbid provided with a gas-outlet, a liquid-chamber, an extended passage formed of immovable walls and connecting the two chambers and provided with a liquid-inlet at one end, said inlet being in communication with the liquid-chamber, the other end of the passage forming an outlet in communication with the generating-chamber said passage being closed except for said inlet and outlet, and a longitudinally-extended stationary body of pervious material obstructing said passage and receiving liquid at the inlet of said passage and conducting it through said passage to the generating-chamber, in a finely-divided condition, whereby the liquid will all be conducted through the length of the pervious material in the passage, the generating-chamber being sealed against access of outer air except for its gas-outlet.

18. In an apparatus for generating acetylene gas, a closed generating-chamber for the carbid provided with a gas-outlet, a liquid-chamber, an extended passage connecting said chambers and provided with a liquid-inlet at one end in communication with the liquid-chamber, its outer end forming an outlet and being in communication with the generating-chamber, the liquid-chamber being located out of the vertical plane of the

outlet end of the extended passage which is in communication with the generating-chamber, said passage being closed except for said inlet and outlet, and a longitudinally-extended body of pervious material obstructing said passage, said body of pervious material extending laterally between the two chambers so that the flow of liquid between the two chambers will be lateral for a portion of its movement and the liquid will be caused to flow through the body of pervious material confined in the extended passage before reaching the generating-chamber.

19. In an apparatus for generating acetylene gas, the combination of a generating-chamber, a liquid-chamber, a passage connecting the two chambers, the liquid-chamber being out of the vertical plane of the opening from said passage into the generating-chamber, an extended body of pervious absorbent material extending laterally between the two chambers and through which the liquid passes from the liquid-chamber to the generating-chamber, whereby the jarring of the liquid-chamber will not interfere with the uniformity of the liquid-feed into the generating-chamber.

20. In an apparatus for generating acetylene gas, the combination of a carbid-chamber provided with a liquid-inlet, a liquid-chamber located out of the vertical plane of the liquid-inlet into the generating-chamber, and a body of pervious absorbent material arranged to conduct liquid from the liquid-chamber laterally to the inlet into the generating-chamber, whereby jarring of the liquid-chamber will not interfere with the uniformity of the feed into the generating-chamber.

21. An acetylene-generator comprising in combination a generating-chamber, a liquid-chamber, a water-passage connecting the chambers and formed by immovable imperforate walls, a stationary packing of pervious material confined between the immovable walls of the water-passage and conducting liquid from the liquid-chamber to the generating-chamber.

In testimony that I claim the foregoing as my invention I affix my signature, in the presence of two witnesses, this 16th day of November, A. D. 1896.

CHARLES W. BECK.
